UNITED STATES PATENT OFFICE.

CHARLES F. HARLOW AND EDWIN E. ANGELL, OF MALDEN, ASSIGNORS TO
THE GLOBE SEWING MACHINE COMPANY, OF BOSTON, MASSACHUSETTS.

FEEDING MECHANISM FOR SEWING-MACHINES.

SPECIFICATION forming part of Letters Patent No. 351,051, dated October 19, 1886.

Application filed October 14, 1885. Serial No. 179,835. (No model.)

To all whom it may concern:

Be it known that we, CHARLES F. HARLOW and EDWIN E. ANGELL, both of Malden, in the county of Middlesex and State of Massachusetts, have jointly invented a new and useful Improvement in Feeding Mechanisms for Sewing-Machines, of which the following, taken in connection with the accompanying drawings, is a specification.

10 The object of this invention is to provide an improved feeding mechanism for sewing-machines and to so arrange the parts as to give the desired movement and regulate the stroke in the simplest manner.

15 Our invention consists in the combination of devices set forth in the appended description and claim.

In the drawings, Figure 1 is a plan view with parts broken away, showing a portion of 20 the feed-bar in horizontal section. Fig. 2 is a vertical central section on line *a a*, Fig. 1; and Fig. 3 is a transverse section on line *xx*, Fig. 1, and Fig. 4 is an enlarged detailed view of the feed-cams and a portion of the feed-bar.

25 A denotes the base of the machine, and A' a standard thereon, serving as a support for the work-plate and affording a bearing for the forward end of the feed and looper shaft E. Secured to the shaft E are two cams, R and R', 30 which may be formed in one piece, (or as a double cam,) and may also be integral with a collar, B, secured to said shaft, as shown in Fig. 2.

35 Q is the feed-bar, which is provided with a vertical offset-shoulder, Q', preferably padded with leather, rawhide, or similar durable non-metallic material. The cam R' impinges against the said shoulder to move the feed-bar forward against the stress of a retracting-spring,

40 S, which latter is connected with the feed-bar and the base A or the standard A'. The feed-bar Q is also provided with a yoke, Q², the horizontal inner faces of which closely embrace the cam R, so that the latter as it revolves

45 imparts positive vertical movements to the feed-bar, there being sufficient play between the vertical faces or ends of said yoke and said cam to permit of the proper horizontal movements of said bar. The feed-bar Q is supported at its rear end by a pin or screw, T,

which passes through a slot in said bar into the standard A'.

U is a laterally-projecting arm secured to or formed integral with the feed-bar Q, said arm being provided with an ordinary serrated feed surface or dog, U'.

Y is an ordinary feed-regulating cam-lever, said lever being preferably recessed on one side for the reception of a buffer, Z, of leather or similar non-metallic material, which is located in line with the yoke Q² of the feed-bar Q so as to serve as a back stop for said feed-bar as the latter is retracted by the spring S. By adjusting the cam-lever Y to different positions the throw of the feed-bar may be regulated in a well-known manner.

The full or acting portions of the cams R and R' are arranged opposite to each other, or nearly so, so as to act alternately on the feed-bar. Thus as the shaft E is rotated the cam 70 R, acting against the upper inner face of the yoke Q², raises the feed-bar to engage the feed-dog U' with the work. The full face of said cam being concentric with the shaft E, the feed-bar is held positively in its elevated position while the full face of the cam R' acts against the shoulder Q' to move the feed-bar and the work forward, and the latter cam holds the feed-bar at the end of its forward throw

75 while the cam R, acting against the lower inner face of the yoke Q², lowers the feed-bar positively, and the said bar is then returned to its first position by the retracting-spring S, thus giving the proper "four-motion" movements to the feed-dog and insuring a noiseless 80 feed, with positive upward, forward, and downward movements.

We are aware that it is not new to operate a feed-bar by means of two oppositely-arranged cams on a rotating shaft, and we do not 90 therefore wish to be understood as claiming this feature, broadly; but

What we do claim, and desire to secure by Letters Patent, is—

In combination with the shaft E, the oppositely-arranged cams R and R' carried thereby, and the feed-bar having a vertical offset-shoulder, against which the cam R' acts, and having also a yoke, the horizontal inner faces of which closely embrace the cam R, with suffi- 100

cient space between the vertical or end walls of said yoke to permit said bar to move horizontally on said cam R, combined with a retracting-spring and feed-regulating lever, substantially as set forth.

In testimony whereof we have signed our names to this specification, in the presence of

two subscribing witnesses, on this 8th day of October, A. D. 1885.

CHARLES F. HARLOW.
EDWIN E. ANGELL.
